(57) CLAIM

The ornamental design for furniture, as shown and described.

DESCRIPTION

FIG. 1 is a front view of a first embodiment of furniture showing our new design;

FIG. 2 is a right-side view thereof, the left-side view being a mirror-image;

FIG. 3 is a top view thereof;

FIG. 4 is a front view of a second embodiment thereof;

FIG. 5 is a front view of a third embodiment thereof;

FIG. 6 is a front view of a fourth embodiment thereof; and, FIG. 7 is a front view of a fifth embodiment thereof.

The broken lines in the drawings, indicating that no particular handle shape is being claimed, represent environmental subject matter and form no part of the claimed design.
